UNITED STATES PATENT OFFICE.

JOHN B. MORGAN, OF PHILADELPHIA, PENNSYLVANIA, ASSIGNOR TO THOMAS WISTAR BROWN AND SUSAN F. WHEELER, OF SAME PLACE.

DESIGN FOR WOVEN FABRIC.

SPECIFICATION forming part of Design No. 24,431, dated June 25, 1895.

Application filed May 20, 1895. Serial No. 550,000. Term of patent 7 years.

To all whom it may concern:

Be it known that I, JOHN B. MORGAN, a citizen of the United States, residing in Philadelphia, Pennsylvania, have invented a new and original Design for Woven Fabric, of which the following is a specification.

My design for a woven fabric is fully shown in the accompanying drawing, which represents sufficient of a piece of the fabric to illustrate the design.

The design comprises a wide stripe A and a narrow stripe B which are separated from each other by intervening stripes of background D, both of the stripes A and B being composed of finer subordinate stripes.

The stripe A comprises a central stripe a flanked on each side by stripes b b of substantially the same width as the stripe a. Beyond each of the stripes b is a stripe d and beyond the latter is a stripe f, these stripes d and f being of substantially the same width and each somewhat narrower than the stripes a and b. Beyond each stripe f is a narrow

stripe g and beyond the latter a wider stripe h, while beyond each of said stripes h is a narrow stripe i, and beyond the latter a wide stripe m.

The stripe B comprises a central wide stripe n flanked on each side by a narrow stripe s and beyond each of the latter is a somewhat wider stripe t and beyond each of the latter a narrow stripe w.

All of the correspondingly lettered stripes are alike and the stripes b h and m are also alike save as to width.

I claim—

The design for a woven fabric, substantially as described and as shown in the accompanying drawing.

In testimony whereof I have signed my name to this specification in the presence of two subscribing witnesses.

JOHN B. MORGAN.
